United States Patent

Des. 237,565
Patented Nov. 11, 1975

237,565

MULTIPLE SUBSTRATE HOLDER

Robert G. Warren, Anaheim, Frederick S. Stearns, Placentia, and Eugene C. Whitcomb, Mission Viejo, Calif., assignors to Rockwell International Corporation, El Segundo, Calif.

Filed Apr. 1, 1974, Ser. No. 456,518

Term of patent 14 years

Int. Cl. D6—99

U.S. Cl. D6—28

FIG. 1 is a perspective view of a multiple substrate holder showing our design.

FIG. 2 is a top view of the same.

FIG. 3 is a bottom view of the same.

FIG. 4 is a side view of the invention as shown in FIG. 1.

The dashed lines shown in FIGS. 2 and 4 are for illustrative purposes only.

We claim:

The ornamental design for a multiple substrate holder, as shown and described.
